Patented Sept. 10, 1918.

UNITED STATES PATENT OFFICE.

CLYDE LOVE TATE, OF PALMER, MASSACHUSETTS.

MOP.

1,278,787.

Specification of Letters Patent. Patented Sept. 10, 1918.

Application filed January 21, 1918. Serial No. 212,853.

To all whom it may concern:

Be it known that I, CLYDE LOVE TATE, a citizen of the United States, residing at Palmer, in the county of Hampden and State of Massachusetts, have invented new and useful Improvements in Mops, of which the following is a specification.

This invention relates to a mop comprising a frame, which may be of circular, triangular, or other form, a handle pivotally connected with the frame and adapted to swing relatively to the plane thereof, and a flexible mop element including a band embracing and clamped on the external surface of the frame, and fibrous filaments depending from said band.

The invention has for its object to provide improved means, for pivotally connecting the handle with the frame, and is embodied in the improvements which I will now proceed to describe and claim.

Of the accompanying drawings forming a part of this specification,—

Figure 1 is a side elevation of a mop embodying the invention, a portion of the frame and a portion of the flexible mop element being shown in section.

Fig. 2 is a top plan view of the mop.

Fig. 3 is a section on line 3—3 of Fig. 2.

Fig. 4 represents in section the handle eye and the tubular spacing members herein-after described, separated from each other.

Fig. 5 is a side view of one of the spacing members.

Fig. 6 is a side view of the pivot-rod herein-after referred to, and the washers forming portions of the heads thereof, the rod and washers being separated.

Fig. 7 is a view similar to Fig. 6, showing a modification.

Fig. 8 is a fragmentary perspective view, illustrating a portion of the frame.

The same reference characters indicate the same parts in all of the figures.

In the drawings, 12 represents a sheet metal frame, here shown as of circular form, although the frame may be of triangular, or other form. The external surface of the frame is concaved to form a channel for the reception of the band forming a part of the flexible mop element herein-after described, the internal surface of the frame being convex.

In opposite portions of the frame are formed orifices 13, (Fig. 8) which receive a pivot-rod 14 extending across the frame and

headed at its opposite ends, the heads bearing on portions of the external surface of the frame. The heads may be formed by upsetting the ends of the rod 14 against washers 15, although, as shown by Fig. 7, one end of the rod may be provided with a head 14^a, the opposite end of the rod being adapted to be upset on a washer 15.

On the rod 14 are strung tubular spacing members 16, which may be of wood, or any other suitable material.

17 represents an eye attached to the inner end of a handle 18, said eye being provided with an orifice 19 adapted to receive the rod 14.

In assembling the parts above described, the eye 17 and the spacing members 16 are introduced into the opening surrounded by the frame, and the rod 14 is then passed through the orifices in the said members and eye and engaged with the frame, as indicated by Fig. 3, the heads formed on the rod as above described, bearing on portions of the external surface of the frame. The outer ends of the spacing members 16 are at the same time caused to bear on portions of the inner surface of the frame, and the inner ends of the spacing members are pressed firmly against opposite sides of the eye 17.

It will now be seen that the handle is pivotally connected with the frame and is spaced from opposite side portions thereof, the handle being adapted to turn or swing relatively to the frame.

The outer ends of the spacing members are provided with concaved faces 20 (Fig. 5) engaging portions of the convex inner surface of the frame in such manner as to prevent the spacing members from turning with the handle.

The inner ends of the spacing members are preferably convex, and the opposite sides of the eye 17 are provided with concaved faces 21, formed to fit said convex inner ends. The area of the surfaces of the spacing members and eye in contact with each other, is therefore greater than would be the case if the opposite sides of the eye and the inner ends of the spacing members were flat.

The parts above described constitute a simple and durable mop-head, adapted to support a flexible mop element composed of a neck or band 22, externally embracing the frame, and fibrous filaments 23 depending from said band, the filaments and the inner

side of the band being clamped on the frame by suitable means, such as a wire ligature 24.

In heading the rod 14, the heads may be caused to exert pressure on the frame tending to force the portions containing the orifices 13 inwardly, thus forcing the inner ends of the spacing members closely against the opposite sides of the eye 17.

As shown by Fig. 4, the eye 17 may be provided with an internally threaded socket 17^a, receiving the threaded inner end of the handle 18.

I claim:

1. A mop comprising a frame provided with orifices in opposite portions, a pivot-rod inserted in said orifices and having heads bearing on portions of the external surface of the frame, a handle having an eye at its inner end adapted to turn on said rod, tubular spacing members mounted on the rod and interposed between the handle eye and portions of the internal surface of the frame, and a flexible mop element in-

cluding a band embracing and clamped on the external surface of the frame and 25 fibrous filaments depending from said band.

2. A mop comprising a frame externally concave and internally convex in cross section, and provided with orifices in opposite portions, a pivot rod inserted in said orifices and having heads bearing on portions of the external surface of the frame, a handle having an eye at its inner end adapted to turn on said rod, tubular spacing members mounted on the rod and interposed between the handle eye and portions of the internal surface of the frame, said spacing members having concave faces at their outer ends engaging the convex inner surfaces of the frame, and a flexible mop element clamped on the external surface of the frame. 35 40

In testimony whereof I have affixed my signature.

CLYDE LOVE TATE.
